Geo. P. Kimmel.

ATTORNEY.

UNITED STATES PATENT OFFICE.

RUSSEL G. SPEIGHT, OF GREENFIELD, MISSOURI.

WRENCH.

1,405,347.

Specification of Letters Patent. Patented Jan. 31, 1922.

Application filed September 13, 1921. Serial No. 500,301.

To all whom it may concern:

Be it known that I, RUSSEL G. SPEIGHT, a citizen of the United States, residing at Greenfield, in the county of Dade and State 5 of Missouri, have invented certain new and useful Improvements in Wrenches, of which the following is a specification.

This invention relates to wrenches of the class especially adapted to engage pipes or 10 rods, and has for one of its objects to simplify the construction and increase the efficiency and utility of devices of this character.

Another object of the invention is to provide a device of this character in which the 15 jaw elements automatically adjust themselves to the pipe or rod, and without the necessity of detaching or adjusting any of the parts.

With these and other objects in view the invention consists in certain novel features of construction as hereinafter shown and described and then specifically pointed out in the claims, and in the drawings illustrative of the preferred embodiment of the 25 invention:

Figure 1 is a side elevation of the improved implement, showing the jaws in intermediate position.

Figure 2 is a side view, partly in section, 30 showing the jaws at the greatest open position.

Figure 3 is a view similar to Figure 2 with the jaws at the least distended position.

Figure 4 is a plan view of a portion of 35 the implement as shown in Figure 1.

The improved implement comprises a shank or stock 10 extended into a handle 11 at one end and with spaced cheek members 40 12 at the other end. The jaw members of the improved implement are pivoted to swing between the cheek members, one of the jaw members being L-shaped.

The L-shaped jaw is formed with a longitudinal portion 13 and a lateral portion 14, the latter having pipe or rod engaging teeth 15.

The longitudinal portion 13 of the L-shaped jaw is pivoted intermediate its ends 50 at 16 between the cheek portions 12.

The other jaw is represented as a whole

at 17 and is provided with opposing pipe or rod engaging teeth 18, and pivoted at 19 intermediate the ends between the cheek portions 12.

The portion 20 of the other jaw 17 bears flatly against the contiguous face of the longitudinal portion 13 of the L-shaped jaw when the jaws are fully open as shown in Figure 2, or when fully closed as shown in Figure 3, to limit the movements when closed or open.

The ends of the jaws between the cheek members are recessed to receive the terminals of a link 21, the latter being pivoted at 22 and 23 to the jaws.

By this arrangement it will be obvious that a simply constructed and efficient pipe and rod wrench is produced which is quickly and automatically adjusted to pipes or rods of various sizes, and which can be cheaply constructed of cast steel and with very little machining or fitting.

The preferred embodiment of the invention is disclosed in the drawing and set forth in the specification, but it will be understood that modifications within the scope of the claimed invention may be made in the construction without departing from the principle of the invention or sacrificing any of its advantages.

Having thus described the invention what is claimed as new is:

1. A wrench comprising a stock, an L-shaped jaw member including a longitudinal portion and a lateral portion and pivoted intermediate the ends of the longitudinal portion to the stock, another jaw member pivoted intermediate its ends to the stock, and a link member coupling the inner ends of the jaws.

2. A wrench comprising a stock having spaced cheek portions at one end, an L-shaped jaw member including a longitudinal portion and a lateral portion pivoted intermediate the ends of the longitudinal portion between the cheek portions, another jaw member pivoted intermediate its ends between the cheek portions, and a link member coupling the inner ends of the jaws between the cheek portions.

3. A wrench comprising a stock, an L-

shaped jaw member including a longitudinal portion and a lateral portion and pivoted intermediate the ends of the longitudinal portion to the stock, another jaw member pivoted intermediate its ends to the stock, a link member coupling the inner ends of the jaws, one of said jaw members having

a portion adapted to bear against the other jaw to limit the travel of the jaws at both ends of their movements.

In testimony whereof, I affix my signature hereto.

RUSSEL G. SPEIGHT.
